(57) **CLAIM**

The ornamental design for a fence section, as shown and described.

DESCRIPTION

FIG. 1 is a front view of a fence section showing my new design;

FIG. 2 is a rear view of the fence section;

FIG. 3 is a right side view of the fence section;

FIG. 4 is a left side view of the fence section;

FIG. 5 is a top view of the fence section;

FIG. 6 is a bottom view of the fence section; and,

FIG. 7 is a top front side perspective view of the fence section.

The broken lines depict portions of the fence section that form no part of the claimed design.

1 Claim, 5 Drawing Sheets
